UNITED STATES PATENT OFFICE

CLEMENT P. GRIFFITH, OF FORT WAYNE, INDIANA, ASSIGNOR TO S. F. BOWSER & COMPANY, INC., OF FORT WAYNE, INDIANA

DESIGN FOR A DOME FOR A LIQUID DISPENSING APPARATUS

Application filed December 15, 1932. Serial No. 46,462. Term of patent 7 years.

To all whom it may concern:

Be it known that I, CLEMENT P. GRIFFITH, a citizen of the United States, residing at Fort Wayne, county of Allen, Indiana, have invented a new, original, and ornamental Design for a Dome for a Liquid Dispensing Apparatus, of which the following is a specification, reference being had to the accompanying drawing, forming part thereof, showing my new design.

The figure is a perspective view of the dome showing my new design.

The design shown in the drawing is of itself a complete article of manufacture.

I claim:

The ornamental design for a dome for a liquid dispensing apparatus substantially as shown and described.

CLEMENT P. GRIFFITH.
